CONVEYER MECHANISM

Myles Morgan, Worcester, Mass., assignor to
 Morgan Construction Company, Worcester,
 Mass., a corporation of Massachusetts

Application January 11, 1944, Serial No. 517,816

10 Claims. (Cl. 198—20)

This invention relates to conveyor mechanism, and more particularly to an improved Y-transfer mechanism suitable for use in conjunction with mills for the rolling of metal bars.

As commonly installed in rolling mills, a Y-transfer mechanism is arranged to receive each bar as it is discharged longitudinally from one stand of rolls and then to swing the rear portion of the bar laterally and to reverse the direction of longitudinal travel of the bar, thereby feeding the bar into a second stand of rolls. The bar enters the transfer mechanism along one line of travel and leaves the transfer mechanism along a line of travel which lies at an acute angle with the entrance line. As heretofore constructed, such a mechanism includes a generally horizontal trough having upright side plates which converge in a direction along the trough, the wide end of the trough being located adjacent the two stands of rolls. A series of power driven reversible rollers extend across the bottom of the trough to support the bars, these rollers being skewed at a considerable angle. This angle of skew is such that when the rollers are driven in one direction to receive a bar, they will cause the bar to travel along one side of the trough, and when the rollers are reversed they will cause the bar to swing laterally and then travel along the other side of the trough. Because of this skewing of the rollers, they necessarily rub continuously against the lower surfaces of the bars while the bars are traveling along the sides of the trough, and in addition the bars are urged laterally into rubbing contact with the side plates. Such rubbing, particularly in the case of bars of aluminum and other soft materials, causes excessive scratching of the bars and results in a product of inferior quality. Furthermore, with the prior construction it is not possible to start rolling a bar for reception on the Y-transfer mechanism until the preceding bar has left the mechanism since the transfer rollers must rotate in one direction to receive a bar and in the reverse direction to deliver the bar. Consequently, the capacity of the mill is unduly restricted.

It is accordingly one object of the invention to provide a Y-transfer mechanism for handling rolled metal bars and so constructed as to substantially eliminate scratching of the bars.

It is a further object of the invention to provide a Y-transfer mechanism having power driven rollers for handling rolled metal bars and so constructed as to substantially eliminate rubbing of the rollers against the bars and rubbing

of the bars against the side plates of the apparatus.

It is a further object of the invention to provide a Y-transfer mechanism so constructed and arranged that it can receive a rolled bar from one roll stand while it is at the same time delivering a preceding bar to a second roll stand.

With these and other objects in view, as will be apparent to those skilled in the art, the invention resides in the combination of parts set forth in the specification and covered by the claims appended hereto.

Referring to the drawings illustrating one embodiment of the invention and in which like reference numerals indicate like parts,

Fig. 1 is a somewhat diagrammatic plan view of a Y-transfer mechanism;

Fig. 2 is a section taken on the line 2—2 of Fig. 1;

Fig. 3 is a section taken on the line 3—3 of Fig. 1;

Fig. 4 is an enlarged section taken on the line 4—4 of Fig. 1;

Fig. 5 is an enlarged view of a portion of Fig. 3, but showing a different phase of the operation; and

Fig. 6 is an electrical wiring diagram showing the means for controlling the motors which drive the apparatus.

The embodiment illustrated comprises a Y-transfer mechanism 10 arranged to receive elongated metal bars as they are discharged from a stand of reducing rolls 11 and to deliver these bars in the reverse direction to a second stand of reducing rolls 12 located near the first rolls 11. In arriving upon the transfer mechanism the bars travel along the line indicated by the arrow 14, and in leaving the transfer mechanism the bars travel along the line indicated by the arrow 15. These two lines of travel are positioned at an acute angle with one another, they being spaced apart rather widely at the reception-delivery end of the apparatus and converging in a direction toward the opposite end. In fact the two lines preferably merge into a common line of travel indicated by the arrow 16, this line preferably forming a rearward extension or continuation of the delivery line 15. Since the bars travel in both directions along the common line 16, this arrow is shown pointed at both ends.

It will be noted that the arrow 14 is directed toward the vertex of the angle between the two lines of travel, whereas the arrow 15 is directed away from the said vertex.

As the bars travel along the above-described

lines of travel, they are supported on power driven horizontal rollers of suitable construction. Thus along the receiving line 14 there is provided a series of spaced conveyer rollers 18, along the common line 16 there is provided a series of spaced conveyer rollers 19, and along the delivery line 15 there is provided a series of spaced conveyer rollers 20. The rollers in each series are arranged with their axes at right angles with the corresponding line of travel, so that they have no tendency to crowd the bars laterally. The receiving rollers 18 are driven by an electric motor M1 through the medium of suitable shaft and gearing connections 22, the common rollers 19 are driven by an electric motor M2 through the medium of suitable shaft and gearing connections 23, and the delivery rollers 20 are driven by an electric motor M3 through the medium of suitable shaft and gearing connections 24. Beyond the common rollers 19 there is mounted a series of spaced idler horizontal rollers 26 with their axes at right angles with the common line of travel 16, these rollers providing a non-driven extension of the series of driven rollers 19. The idler rollers 26 may be continued as far as is necessary to support the front portion of each bar as the rear end thereof leaves the first roll stand 11. The spaces between the various rollers are filled with substantially horizontal plates 28, and upright flanges or side guards 29 are provided adjacent the outer ends of the rollers. This construction provides a trough having side walls which converge for a portion of its length and then continue parallel to one another for the remainder of its length.

Means is provided to shift the bars laterally from the receiving rollers 18 to the delivery rollers 20. For this purpose the trough bottom 28 is formed with a series of transverse slots or grooves 31 therein, and along each of these slots there extends the upper run of an endless chain 32 having dogs 33 thereon arranged to project upwardly through the slot. These dogs are pivotally connected to the chains, and each slot 31 is formed with a deep pocket 35 into which the dogs may drop as they reach the delivery rollers 20, as shown in Fig. 5. Thus the dogs may push the bars laterally across the bottom of the trough and then pass beneath the bars. Each chain is shown provided with three of the dogs 33, equally spaced along its length. At the receiving side of the trough the chains 32 are supported on idler sheaves 37, and at the delivery side they are supported on sprocket wheels 38 mounted on a common rotatable shaft 39 driven by an electric motor M4. A suitable limit switch 40 is driven from the shaft 39.

In some installations it may be desirable to arrange for automatic control of the motor M2 which drives the common series of rollers 16. For this purpose a bar-detecting device in the form of a flag 42 is mounted at the bottom of the trough in position to be actuated by each bar as it is shifted from the receiving line 14 to the delivery line 15. This flag is located near the junction of the receiving line and the delivery line. As best shown in Fig. 4, the flag is pivotally mounted, and it is connected by a rod 43 to a limit switch 44 of suitable construction. A coiled tension spring 45 holds the flag yieldably in a raised position.

Referring now to Fig. 6, the electrical apparatus is supplied with electricity from a suitable source 47 through a main switch 48. The motor M1 is controlled by a manually operable lever 50 which

actuates two normally open switches 51 and 52 in opposite directions. The switch 51 is connected in series with a coil F1 and the switch 52 is connected in series with a coil R1. The coil F1 serves to close two switches F1A and F1B which are connected in the circuit of the motor M1 to cause operation thereof in a forward direction and convey the bars as indicated by the arrow 14 of Fig. 1. The coil R1 serves to close two switches R1A and R1B which are connected in the circuit of the motor M1 to cause operation thereof in a reverse direction. Ordinarily there will be no occasion for reverse operation of this motor.

The motor M2 is controlled by a manually operable lever 54 which actuates two normally open switches 55 and 56 in opposite directions. The switch 55 is connected in series with a coil F2, and the switch 56 is connected in series with a coil R2. The coil F2 serves to close two switches F2A and F2B which are connected in the circuit of the motor M2 to cause operation thereof in a forward direction. The coil R2 serves to close two switches R2A and R2B which are connected in the circuit of the motor M2 to cause operation thereof in a reverse direction.

The motor M3 is controlled by a manually operable lever 58 which actuates two normally open switches 59 and 60 in opposite directions. The switch 59 is connected in series with a coil F3, and the switch 60 is connected in series with a coil R3. The coil F3 serves to close two switches F3A and F3B which are connected in the circuit of the motor M3 to cause operation thereof in a forward direction and convey the bars as indicated by the arrow 15 of Fig. 1. The coil R3 serves to close two switches R3A and R3B which are connected in the circuit of the motor M3 to cause operation thereof in a reverse direction. Ordinarily there will be no occasion for reverse operation of this motor.

When the motor M2 is to be controlled automatically rather than manually, certain additional switches are required. For this purpose the flag 42 is arranged to operate a normally closed switch 62 and a normally open switch 63, both of which are part of the limit switch construction indicated by the reference numeral 44 in Fig. 4. The switch 62 is connected in series with the coil F2 and with a normally open switch F1C controlled by the coil F1. The switch 63 is connected in series with the coil R2 and with a normally open switch F3C controlled by the coil F3. A manually operable selector switch 65 is also provided, this switch being movable between an "automatic" position shown in full lines and a "manual" position indicated in broken lines. In the "automatic" position of the selector switch, the switches F1C and F3C are both connected to the source 47, and the switches 55 and 56 are rendered ineffective. In the "manual" position of the selector switch, the switches 55 and 56 are both connected to the source 47, and the switches F1C and F3C are rendered ineffective.

The motor M4 is connected in series with a switch 68 which can be closed by a coil 69, this coil being connected in series with the limit switch 40. This limit switch is shunted by a normally open manually operable switch 70, which may be of the push-button type.

The operation of the invention will now be apparent from the above disclosure. To prepare the Y-transfer mechanism for the reception of the first bar, the operator will close the main switch 48, place the selector switch 65 in the "automatic" position, and place the lever 50 in

the "forward" position, thereby closing switch 51 and energizing coil F1, which in turn will close switches F1A, F1B and F1C. Closing F1A and F1B will start motor M1 in a forward direction, and closing F1C will energize coil F2, closing switches F2A and F2B, and starting motor M2 in a forward direction. Consequently the receiving rollers 18 and the common rollers 19 will operate in a forward direction, the surface speed of these rollers preferably being equal to the delivery speed of the roll stand 11. As the bar leaves the rolls 11, it will be supported by the rollers 18 and 19, and in the case of a very long bar its front portion will eventually pass over the idler rollers 26. After the rear end of the bar has left the rolls 11, the operator will return the lever 50 to its neutral position, opening switch 51, de-energizing coil F1, and opening switches F1A, F1B and F1C. Opening switches F1A and F1B will stop motor M1, and opening switch F1C will de-energize coil F2, opening switches F2A and F2B, and stopping motor M2. Thus the rollers 18 and 19 will stop, and the bar will come to rest. The operator will then close push buttons 70, energizing coil 69, closing switch 68 and starting motor M4. This will drive the transfer chains 32, and the dogs 33 will move ahead, transferring the rear portion of the bar laterally from the receiving rollers 18 to the delivery rollers 20. As the dogs start to move, the limit switch 40 will close, so that the operator can then release the push button 70 without any effect. When the bar has reached the rollers 20, the dogs 33 will drop into the pockets 35 and pass beneath the bar and beyond the trough. At this time the limit switch 40 will open, deenergizing coil 69, opening switch 68, and stopping the motor M4 and the chains 32. As the bar reaches the rollers 20, it will depress the flag 42, opening switch 62 and closing switch 63. The operator will now move lever 58 to its forward position, closing switch 59, energizing coil F3, and closing switches F3A, F3B and F3C. Closing F3A and F3B will start motor M3 in a forward direction to drive the rollers 20 and move the bar in the direction of the arrow 15 toward the second stand of rolls 12. Closing F3C will energize coil R2, closing switches R2A and R2B, and starting motor M2 and common rollers 19 in the reverse direction, which corresponds to the forward direction of the delivery rollers 20. The operator can now place the lever 50 in its forward position once more, closing switch 51, energizing coil F1, and closing switches F1A, F1B and F1C. Closing F1A and F1B will start motor M1 and the receiving rollers 18 in a forward direction, so that the next bar can be started through the roll stand 11. Closing F1C will have no effect so long as switch 62 is open, but the instant the first bar has left the flag 42, the spring 45 will elevate the flag, opening switch 63 and closing switch 62. Consequently, coil R2 will be de-energized and coil F2 will be energized. Switches R2A and R2B will open, switches F2A and F2B will close, and motor M2 will once more drive the common rollers 19 in a forward direction to receive the approaching second bar. As the first bar leaves the delivery rollers 20, the operator will return the lever 58 to its neutral position, opening switch 59, de-energizing coil F3, opening switches F3A and F3B, and stopping motor M3.

In case the operator wishes to control the motor M2 manually, he will place the selector switch 65 in its "manual" position. This will permit him to control the energization of the coils F2

and R2 manually by means of the lever 54 and the switches 55 and 56. Under these conditions the flag switches 62 and 63, as well as the switches F1C and F3C, will be out of circuit and hence of no effect.

It will be noted that during its travel out of the first roll stand 11 and also during its approach to the second roll stand 12, each bar is supported on horizontal rollers arranged with their axes at right angles with the direction of travel. There is no rubbing of the rollers against the bars, and no lateral crowding of the bars against the sides of the trough. Consequently, scratching of the bars is substantially eliminated. The invention also makes it possible to increase the rate of production, since it is unnecessary to await the passage of each bar through the second roll stand before starting the next bar through the first roll stand.

Having thus described my invention, what I claim as new and desire to secure by Letters Patent is:

1. A Y-transfer mechanism for handling elongated bars comprising two series of substantially horizontal rollers arranged in two substantially horizontal lines which converge at an acute angle, the axes of the rollers being located substantially at right angles with the respective lines, means to drive one series of rollers in a direction to move the bars longitudinally toward the vertex of the said angle, means to transfer the bars laterally from the rollers of the said one series to the rollers of the other series, and means to drive the said other series of rollers in a direction to move the bars longitudinally away from the said vertex.

2. A Y-transfer mechanism for handling elongated bars comprising a series of substantially horizontal power driven receiving rollers arranged to receive the bars as they move longitudinally along one line of travel, the axes of the rollers being located substantially at right angles with the said line of travel, a series of substantially horizontal power driven delivery rollers arranged to deliver the bars longitudinally in the opposite direction along a second line of travel, the axes of the delivery rollers being located substantially at right angles with the said second line of travel, the two lines of travel being positioned at an acute angle and converging in the direction of bar movement along the receiving rollers, and means to transfer the bars laterally from the receiving rollers to the delivery rollers.

3. A Y-transfer mechanism for handling elongated bars comprising a substantially horizontal trough having opposed upright side walls which converge at an acute angle, a first series of conveyer rollers extending in a row along one of the side walls and arranged to move the bars longitudinally in the direction of trough convergence, a second series of conveyer rollers extending in a row along the other side wall and arranged to move the bars longitudinally in the direction of trough divergence, and means to transfer bars laterally from the first series of rollers to the second series of rollers.

4. A Y-transfer mechanism for handling elongated bars comprising a substantially horizontal trough having opposed upright side walls which converge at an acute angle, a first series of conveyer rollers arranged in a row adjacent one of the side walls with their axes substantially at right angles therewith, a second series of conveyer rollers arranged in a row adjacent the other of said side walls with their axes substantially at right angles therewith, means to drive

the first series of rollers in a manner to move the bars longitudinally in the direction of trough convergence, means to drive the second series of rollers in a manner to move the bars longitudinally in the direction of trough divergence, and means to transfer bars laterally from the first series of rollers to the second series of rollers.

5. A Y-transfer mechanism for handling elongated bars comprising two series of conveyer rollers arranged in two rows which converge at an acute angle, means to drive the first series of rollers in a direction to move the bars longitudinally toward the vertex of the said angle, means to drive the second series of rollers in a direction to move the bars longitudinally away from the said vertex, a third series of conveyer rollers arranged in a row extending beyond the said vertex and in position to receive the front portion of each bar while the rear portion thereof rests upon the rollers of the first series, means to transfer the said rear portion of each bar laterally from the first series of rollers to the second series of rollers, and means to drive the third series of rollers first in a direction to receive a bar from the first series of rollers and then in the reverse direction to deliver the bar to the second series of rollers.

6. A Y-transfer mechanism for handling elongated bars comprising a substantially horizontal trough having opposed upright side walls which converge at an acute angle throughout a portion of the length of the trough and then continue parallel with one another to provide a straight portion of the trough, a first series of conveyer rollers arranged in a row within the converging portion of the trough adjacent one of the side walls with their axes substantially at right angles therewith, a second series of conveyer rollers arranged in a row within the converging portion of the trough adjacent the other of said side walls with their axes substantially at right angles therewith, means to drive the first series of rollers in a manner to move the bars longitudinally in the direction of trough convergence, means to drive the second series of rollers in a manner to move the bars longitudinally in the direction of trough divergence, a third series of conveyer rollers arranged in a row within the straight portion of the trough in position to receive the front portion of each bar while the rear portion thereof rests upon the rollers of the first series, means to transfer the said rear portion of each bar laterally to the second series of rollers, and means to drive the third series of rollers first in a direction to receive a bar from the first series of rollers and then in the reverse direction to deliver the bar to the second series of rollers.

7. A Y-transfer mechanism for handling elongated bars comprising two series of conveyer rollers arranged in two rows which converge at an acute angle, means to drive the first series of rollers in a direction to move the bars longitudinally toward the vertex of the said angle, means to drive the second series of rollers in a direction to move the bars longitudinally away from the said vertex, a third series of conveyer rollers arranged in a row extending beyond the said vertex and in position to receive the front portion of each bar while the rear portion thereof rests upon the rollers of the first series, the third series of rollers being aligned with the second series of rollers, means to transfer the said rear portion of each bar laterally to the second series of rollers, and means to drive the third series of rollers first in a direction to receive a bar from the first series of rollers and then in the reverse direction

to deliver the bar to the second series of rollers.

8. A Y-transfer mechanism for handling elongated bars comprising a substantially horizontal trough having opposed upright side walls which converge at an acute angle throughout a portion of the length of the trough and then continue parallel with one another to provide a straight portion of the trough, one of the side walls continuing in a single straight line and the other side wall being formed in two portions which meet at an obtuse angle, a first series of conveyer rollers arranged in a row within the converging portion of the trough adjacent the said other side wall, means to drive the first series of rollers in a manner to move the bars longitudinally in the direction of trough convergence, a second series of conveyer rollers arranged in a row within the converging portion of the trough adjacent the said one side wall, means to drive the second series of rollers in a manner to move the bars longitudinally in the direction of trough divergence, a third series of conveyer rollers arranged in a row within the straight portion of the trough in position to receive the front portion of each bar while the rear portion thereof rests upon the rollers of the first series, means to transfer the said rear portion of each bar laterally to the second series of rollers, and means to drive the third series of rollers first in a direction to receive a bar from the first series of rollers and then in the reverse direction to deliver the bar to the second series of rollers.

9. A Y-transfer mechanism for handling elongated bars comprising two series of conveyer rollers arranged in two rows which converge at an acute angle, means to drive the first series of rollers in a direction to move the bars longitudinally toward the vertex of the said angle, means to drive the second series of rollers in a direction to move the bars longitudinally away from the said vertex, a third series of conveyer rollers arranged in a row extending beyond the said vertex and in position to receive the front portion of each bar while the rear portion thereof rests upon the rollers of the first series, the third series of rollers being aligned with the second series of rollers, means to transfer the said rear portion of each bar laterally to the second series of rollers, a bar-detecting device located in line with the second and third series of rollers and near the said vertex, the said device being arranged to respond to the said lateral transfer of each bar, separate manual controls for the driving means of the first and second series of rollers, reversible driving means for the third series of rollers, and a control for the said reversible driving means responsive to the said device and to the said manual controls so arranged that the third series of rollers will operate in the same direction as the second series of rollers when a bar is in position to actuate the device and in the same direction as the first series of rollers when a bar is not in a position to actuate the device.

10. A Y-transfer mechanism for handling elongated bars comprising two series of conveyer rollers arranged in two rows which converge at an acute angle, an electric motor to drive the first series of rollers in a direction to move the bars longitudinally toward the vertex of the said angle, a second electric motor to drive the second series of rollers in a direction to move the bars longitudinally away from the said vertex, a third series of conveyer rollers arranged in a row extending beyond the said vertex and in position

to receive the front portion of each bar while the rear portion thereof rests upon the rollers of the first series, the third series of rollers being aligned with the second series of rollers, a reversible electric motor to drive the third series of rollers, means to transfer the said rear portion of each bar laterally to the second series of rollers, a bar-detecting device located in line with the second and third series of rollers and near the said vertex, the said device being arranged to respond to the said lateral transfer of each bar, separate manually operable switches for control-

5 ling the motors for the first and second series of rollers, a reversing switch for the reversible motor, and means to control the said reversing switch responsive to the said device and to the said manually operable switches so arranged that the third series of rollers will operate in the same direction as the second series of rollers when a bar is in position to actuate the device and in the same direction as the first series of rollers when a bar is not in a position to actuate the device.

MYLES MORGAN.
